UNITED STATES PATENT OFFICE.

CHARLES W. HUDSON, OF WEEDSPORT, NEW YORK.

DESIGN FOR A FRAME FOR PULLEY-LINE RIDERS.

SPECIFICATION forming part of Design No. 27,144, dated June 1, 1897.

Application filed November 30, 1896. Serial No. 614,006. Term of patent 7 years.

To all whom it may concern:

Be it known that I, CHARLES W. HUDSON, a citizen of the United States, residing at Weedsport, in the county of Cayuga and State 5 of New York, have invented and produced a new and original Design for a Frame for Pulley-Line Riders, of which the following is a specification, reference being had to the accompanying drawings, in which—

10 Figure 1 is a side view of my design for a frame for a rider for pulley-lines. Fig. 2 is an edge view thereof.

As shown in the drawings, the leading feature of my design consists in a frame for a 15 rider for pulley-lines having a bifurcated base, the outside lines of the sides diverging as it approaches the lower end and the upper end provided with a bracket terminating in a gooseneck, the whole forming a unitary article of manufacture.

a is the base, bifurcated and having diverging parts *b*.

c is the bracket, terminating in the gooseneck, having its top rounded, as shown at *d*.

e f are straps securing the neck and bifurcated bottom together. 25

Having described my invention, what I claim, and desire to secure by Letters Patent, is—

The design for a frame for a rider for pulley-lines substantially as herein described and shown. 30

In witness whereof I have hereunto set my hand this 28th day of November, 1896.

CHARLES W. HUDSON.

In presence of—

F. N. BURRITT,
FRED M. HARRINGTON.
